US0D1070588S

(12) **United States Design Patent** (10) Patent No.: **US D1,070,588 S**
(45) Date of Patent: ** Apr. 15, 2025

(54) **CLOSEABLE CARTON**(71) Applicant: **Inno-Pak, LLC**, Delaware, OH (US)(72) Inventor: **Steven A. Mayer**, Indianapolis, IN (US)(73) Assignee: **Inno-Pak, LLC**, Delaware, OH (US)(***) Term: **15 Years**(21) Appl. No.: **29/727,102**(22) Filed: **Mar. 9, 2020**(51) LOC (15) Cl. **09-03**

(52) U.S. Cl.

USPC ..... **D9/433**(58) **Field of Classification Search**USPC D9/414, 416, 420, 424, 430, 431, 432, D9/433, 721; D3/211, 201, 203.6, 242; D7/601, 602
